CLAIM

The ornamental design for a fire control selector, as shown
and described.

DESCRIPTION

FIG. 1 is a perspective view of a fire control selector in
accordance with an embodiment of the present design;
FIG. 2 is a right side elevation view of the fire control selector
of FIG. 1;

FIG. 3 is a left side elevation view of the fire control selector
of FIG. 1;

FIG. 4 is a back view of the fire control selector of FIG. 1;
FIG. 5 is a front view of the fire control selector of FIG. 1;
FIG. 6 is a top view of the fire control selector of FIG. 1; and,
FIG. 7 is a bottom view of the fire control selector of FIG. 1.
The broken lines shown in FIGS. 1, 4, and 5 are presented for
illustrative purposes only and form no part of the claimed
design.

1 Claim, 3 Drawing Sheets
